ENGINE STARTER

Roland Chilton, Ridgewood, N. J.

Application March 3, 1938, Serial No. 193,808

2 Claims. (Cl. 74—7)

My invention relates to starters, and particularly to starters for aeronautical engines.

A prime object of the invention is to provide a starter and associated gearing of greater compactness than that obtaining in conventional designs, or alternately, to provide greater torque capacity within current dimensions.

It will be understood that these starters mount on engine accessory sections where they are surrounded by magnetos, generators, oil pumps, fuel pumps, etc., resulting in extreme congestion. The demands upon, and accordingly, the dimensions of, the various accessories tend to increase as the art develops. This development also introduces additional accessories from time to time. Great difficulty, therefore, is now experienced in meeting all of the requirements in the space available on current engines.

In the case of the starter, the necessary high ratio reduction gearing is the bulkiest element, and this gearing is normally placed at the engine end of the starter with the electric motor mounted on the rear. The diameter of the motor is a relatively small dimension but, in most cases, it is found that the worst interferences with adjacent accessories occur at the engine end of the starter. Accordingly, in this invention, novel means are provided whereby the normal disposition may be reversed and the gearing placed at the end of the starter remote from the mounting flange whereat, due to the relative shortness of certain of the other accessories, more space is afforded.

Another object of the invention is to provide a novel planetary cage structure permitting the use of an abnormally large number of gear driven planet pinions whereby the capacity of a gear of given diameter is substantially increased.

Other objects and advantages of the invention will be obvious from, or will be pointed out in, the following description with reference to the drawings, in which:

Fig. 1 comprises axial half sections through the starter, the upper portion showing the parts in engaged condition and the lower portion showing the parts disengaged;

Fig. 2 comprises segmental transverse sections in which segment (a) is on the line "a" of Fig. 1, segment (b) is on the line "b" of Fig. 1, and segment (c) is on the line "c" of Fig. 1;

Fig. 3 is a perspective detail view of a planet member;

Figs. 4 and 5 are detail views of a split friction ring;

Fig. 6 is an end view of a standard three-way starter jaw, and

Fig. 7 is an end view of a fine tooth jaw associated with the standard jaw in this invention.

Referring first to Fig. 1, 10 designates a field frame of an electric motor having a front flange 12 and a rear flange 14. A cover member 16 having a bearing housing 18 is secured to the motor flange 12 and both are drilled for the standard engine mounting studs indicated by the dotted lines at 20. The motor has brushes indicated in general at 22 engaged with a commutator 24 of more than normal length to permit bodily axial movement of the armature from the disengaged position shown in the lower half of Fig. 1 to the engaged position indicated in the upper half. The disengaged position of the armature is offset 15 axially from the center of the field to effect this automatic magnetic mesh.

Carried along with the armature during this engaging motion are the following elements:

The tubular armature shaft 26 which has 20 splines 28 at its rearward end is slidable in a hub 30 of a driving gear 32. At its inner end the armature shaft carries rigidly a sleeve 34 having an enlarged annular portion 36 within which is frictionally engaged a spring cuff member 38 (seen 25 in detail views of Figs. 4 and 5) having a projecting key member 40 which is engaged with a slot 42 formed in the periphery of an engine engaging jaw 44 having the standardized three jaw engagement with a companion jaw on the engine to be 30 started and indicated by dotted lines at 46.

The back of the engine jaw 44 is equipped with very fine ratchet teeth 48 and engaged with these teeth is a companion ratchet member 50 (also shown in Fig. 7), which member has splines 52 35 slidable on a main driving shaft 54 (which does not partake of the axial movement). The ratchet teeth 48 are urged into engagement by a light spring 56. The parts above described are urged to the disengaged or right hand position (of the lower half of Fig. 1) by a long spring 58 disposed in a bore in the shaft 54 and engaging a long tension rod 60 through a bushing 62, this rod being secured to the engine engaging jaw 44 by a suitable head member 64.

As before stated, the main shaft 54, on which the hollow armature 26 rotates and slides axially on split bushings 66, does not partake of this axial motion, being provided at its right hand end with a flange 68 and with a suitable outboard support bearing 70. An internally toothed gear 72 is secured to the flange 68 by screws 74.

Around the hub 39 of the driving gear 32, previously described as splined to the armature shaft 26, there is rotatably floated, on a bushing 76, a 55

cage member comprising a hub 78 and a flange 80 which has a circumferential plurality of bearing bores 82. Aligned with the bores 82 are companion bores 83 formed in a rim 84 extending from a flange 86 secured by bolts 88 to the member 80 to form a composite planet carrier. This carrier, it may be pointed out, comprises an important feature of the present invention. The member 84-86 is shown in detail in the perspective view 10 of Fig. 3 which is turned end-for-end with respect to Fig. 1 in order to better show the construction. Two of the tapped holes in the in-turned flange member 86, whereby the cage elements are secured together, appear in this view which also shows all 15 of the plurality of bearing bores in the rim 84. It will be seen that the outside diameter of this rim will clear the tips of the teeth in the ring gear 72 while the inner diameter clears the tops of the teeth of the driving gear 32. Back of the rim 84 20 the member has counterbores extending through to the rear face of the flange 86, these counterbores being large enough to clear the tops of the teeth of planet pinions later to be described. These counterbores define intermediate hollow 25 sided stumps, seen in transverse section at 99 (Fig. 2-c), which stumps integrally unite the rim 84, and the flange 86 which is assembled rigidly with the companion flange 80, by the screws 89, as previously described.

30 Supported in this composite cage structure are a plurality of composite planets comprising right hand pinions 92, having extending journal shafts 94-96, to the latter of which is fitted a second pinion 98. This latter pinion is clamped for unitary rotation with the pinion 92 by means of nuts 100, distance pieces 102 and spacer washers 104. The pinions 98 engage with a ring gear 106 splined into a housing 108 to comprise the fixed member of the differential planetary gear. 35

40 The housing 108 has bars 110 (also seen in section 2-a) integral with a flange 112 by which the gear housing is secured to the motor flange 14 by long tubular nuts 114. The housing is provided with a cover 116 to enclose the brush gear and with a gear housing 118 which supports the outboard bearing 70 previously described.

45 The operation of the starter is as follows: As soon as the motor is energized it drives the gear 32 through the spline connection at the hub 30 and this gear in turn causes the pinions to planetary with the cage 86-84. The fixed annular gear 106 has a slight differential in tooth member relative to the driven gear 72 which is, accordingly, rotated at reduced speed, driving the main shaft 54 through the flange 68 and with it the ratchet jaw 52; these parts comprising the low speed, high torque elements of the starter. Simultaneously with energization of the motor, the armature shaft is moved leftward by the 50 offset disposition of the armature, under the magnetic pull from the motor field 10, establishing axial contact with the standard three-tooth jaw 44 with the engine jaw 46. It will be seen that these jaws afford a possible one-third of a turn rotational backlash which, in the case of a 55 typical reduction ratio of 120 to 1, corresponds to 40 turns of the motor armature, during which it is free, in conventional starters, to accelerate under no-load, which would produce destructive impacts due to the flywheel effect of the high speed motor armature. However, the starter jaw 44 is at all times lightly urged to rotate with

the sleeve member 36 (already described as rigid with the armature) by the friction cuff 38, and will so rotate until arrested by complete rotational engagement of the jaws 44-46; this overrunning of the jaw 44 being permitted by the 5 ratchet teeth 48 which take up the starting drive at slow speed from the gearing the instant the jaw 44 is so arrested.

It will also be seen that by the novel disposition here disclosed the reduction gearing is disposed at the rear end of the starter where it is more accessible and where there is, in general, more room on current engines than at the conventional disposition next to the mounting flange. It will also be seen that, by the novel planet cage 15 disposition of this invention, it is possible to accommodate a very large number of planet pinions meshed with a central gear whereby the capacity of the gear may be increased and/or its diameter reduced.

20 While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

25 I claim as my invention:

1. In an engine starter organization, a casing 30 having an inner end portion of substantially less diameter than the outer end portion thereof, said inner end portion being adapted for attachment to the engine, an engine-engaging jaw, a low speed drive shaft organized for unitary rotation 35 with said jaw, said drive shaft being substantially coextensive in length with the overall length of said casing, an armature rotatable on said shaft within the small diameter inner end portion of said casing, and reduction gearing 40 drivably connecting said shaft and armature, said reduction gearing having an overall diameter greater than that of said armature and being wholly confined within the larger diameter outer end portion of said casing.

45 2. In an engine starter organization, a casing having an inner end portion and an outer end portion, said two portions being adapted for attachment one to the other, and said inner end portion having an overall diameter substantially 50 less than the corresponding diameter of said outer end portion whereby the latter is adapted to overhang the circle of bolt holes through which the bolts for attaching the starter to the engine extend, an engine-engaging jaw, a low 55 speed shaft organized for unitary rotation with said jaw, said shaft being substantially coextensive in length with the overall length of said casing and being mounted concentrically therewithin, an armature rotatable upon said shaft, 60 said armature being confined within the smaller diameter inner end portion of said casing, and reduction gearing drivably connecting said armature and shaft, said reduction gearing having an overall diameter greater than the corresponding 65 diameter of said armature, and all of said gearing being disposed on the opposite side of said armature to said jaw and being wholly confined within the larger diameter outer end portion of said casing.

70 ROLAND CHILTON.
